ATTORNEY.

UNITED STATES PATENT OFFICE.

JOHN C. KEMP, OF OTTERBEIN, INDIANA.

CARBID-FEEDING MECHANISM.

SPECIFICATION forming part of Letters Patent No. 699,394, dated May 6, 1902.

Application filed June 19, 1901. Serial No. 65,112. (No model.)

To all whom it may concern:

Be it known that I, JOHN C. KEMP, a citizen of the United States, residing at Otterbein, in the county of Benton and State of Indiana, 5 have invented certain new and useful Improvements in Carbid-Feeding Mechanism; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to devices whereby the carbid used in producing acetylene gas may be automatically fed in proper quantities or so admitted to the water for generating the gas, and it has reference more particularly to the devices comprising the regulating or feed valve.

The invention also has reference to the vessel in which the carbid is stored and the vessel in which the gas is produced.

25 My object is to provide devices of the above character which may be reliable operatively and durable and at the same time be cheaply constructed, so as to be adapted particularly for domestic purposes, as well as for larger 30 gas plants.

Another and no less important object is to provide apparatus which shall be free from the dangers of explosion from overpressure.

Referring to the drawings, Figure 1 represents a gas-generator embodying my improvements and a gasometer of common type connected therewith, the view being in vertical central section; Fig. 2, a fragmentary detail view showing the feed-valve in contact with 35 the upper seat in the valve-case, and Fig. 3 a fragmentary detail view showing the feed-valve in contact with the lower seat in the valve-case.

In the drawings similar reference characters in the several figures indicate corresponding parts.

Broadly considered, the invention comprises as the principal elements a valve-case having two opposing valve-seats and a double-acting 40 valve in the case adapted to operate upon either of the valve-seats for regulating the

supply of carbid and also for cutting off the supply when necessary.

The invention also comprises a generator vessel having a stationary upper vessel or 55 gas-receiver having a water seal, and it also includes a carbid-holder connected with the valve-case which is of novel form, the holder, the valve-case, and the gas-generating chamber being in communication.

Considered specifically, in construction I provide a circular valve-case *a*, which as constructed is clear internally and is provided at its lower end with a valve-seat *d*, facing upwardly, and at its upper end with a valve-seat *e*, facing downwardly, the case being swelled or enlarged intermediately of the valve-seats. As preferably formed, the lower portion of the case, considered in the relation in which it is used, is in the well-known form 70 of a funnel, having relatively long sloping sides *6*, at the broader upper portion *7* of which it is joined by the upper portion of the case, which is also in the shape of a funnel, having relatively short sloping sides, but inverted in relation to the lower portion of the case, the smaller ends of the funnels being open and the inner edges of the orifices forming the opposing valve-seats *d* and *e*, respectively; otherwise the case is imperforate. 75 The case may be suitably supported and connected, so that the carbid escaping therefrom may be conveyed to the generating vessel of any suitable type.

In the case *a*, as above described, is a double-acting valve *b*, formed substantially in the shape of two cones having their bases abutting and joined together, the apexes of the cones being the ends of the valve. Thus the part of the valve having the greater diameter, as at 1, is the line at which the cones join, and as one cone is preferably longer than the other that portion 1 is not midway between the ends of the valve, being in the present case below the middle of the valve, 95 so that the sides 4 from 1 to 2 are shorter than the sides 5 from 1 to 3. The slope or angularity of the sides 4 preferably correspond in degree to the angular slope of the sides 6 of the case, while the slope of the sides 5 is less acute in degree. The valve *b* is provided with a combined operating-rod and axial

guide-stem *c*, that portion thereof above the valve operating in a suitably-supported guide *f* and that portion below the valve operating in a suitably-supported guide *g* and extending 5 below the guide *g* as an operating-rod, the lower end or any suitable portion of which is provided with a weight *8* when the valve itself is not sufficiently weighty to insure the desired results in causing the valve to descend by the force of gravity. Any suitable means may be employed for automatically elevating the valve *b* in operation.

The vessel which I preferably employ in which to produce the gas and to which the 10 valve-case may be directly connected comprises a circular tank *j*, adapted to retain water, and in the tank a somewhat similar vessel, inverted, so as to be substantially similar to a "bell" of a gasometer, which may be 15 termed the "receiver" *k*, somewhat smaller in diameter than its tank *j* and having a cover *l* inclosing its top, the cover having projections extending to the top of the tank *j*, to which the receiver is secured by suitable 20 screw-nuts *y* and screw-studs or by other suitable means. The tank *j* has a funnel-shaped bottom *m*, having a suitable gate-valve *n*, through which the slaked carbid and foul water may be removed.

25 A guide *o* is suitably supported in the tank *j*, and operatively mounted in the guide is a vertical push-bar *p*, having a weight *9* arranged so as to engage the weight *8*, but preferably is not attached thereto, although usually in contact in operation. A lever *q* is pivoted between its ends and is connected at one end thereof to the lower end of the bar *p* and at the other end thereof to a connecting push-rod *r*, that extends upwardly between the walls of the tank *j* and the receiver *k* to a suitable height and having a lug *s* attached thereto, the lug being in the path of a finger *t*, suitably operated, the finger in the present case being attached to the top of the bell *u*, of common form, arranged in a tank *v* for receiving and storing the gas, from which the gas may be distributed through a service-pipe *x*. The gas may be conveyed from the generator to the gasometer by means of a 30 pipe *w*, extending from a point near the cover *l* nearly to the lower portion of the bottom *m*, thence into the bell *u*, and to the plane of the top of the tank *v*, or thereabout.

The numerals 10 and 11 indicate the approximate height at which the sealing-water is maintained in the respective tanks.

50 The guide *g* is preferably secured to the case *a*, so as to be practically a part thereof, and detachably connected to the cover *l*, so that a gas-tight joint is formed.

A hopper *h* is secured to the case *a* above the seat *e*, and it has a suitable filling-plug *i* or an equivalent cap. In this construction the guide *f* is supported in the hopper *h*.

55 In operation it will be understood that the hopper is to be supplied with carbid, my experience being that one-fourth inch size is

satisfactory, and the valve *b* permitting small quantities of the carbid to drop into the sealing-water in the tank *j*, gas is formed in the receiver *k* above the water, and there being no other avenue of escape under normal conditions passes through the pipe *w* into the bell *u*, causing the bell to rise, thus permitting the push-bar *p* to descend, and with it 70 the valve *b*, unless arrested by particles of carbid which may lodge between the valve and its case or the lower seat *d*. Should the valve not entirely close, the carbid would almost or entirely cease passing down, and 80 if a few grains descend these may balance the amount of gas that may be consumed. In practice, however, these particles pass down almost immediately, thus allowing the valve to close and arrest the production of gas, 85 the carbid above the valve and the weight *8* forcing the valve to its lower seat, where it would remain until the supply of gas in the bell *u* would diminish and allow the bell to descend, when the valve *b* would be again 90 pushed up to feed more carbid into the water below. Usually in operation the valve *b* would be nearly in mid-position between its seats, feeding more or less continually. It is designed that before the supply of gas in the 95 bell *u* is exhausted after the carbid in the hopper *h* has been consumed the valve *b* will have been pushed against its upper seat *e*, when it will prevent gas from entering the hopper. Then the hopper may be refilled while 100 the gas is still being used. In this case the lug *s*, which should be suitably arranged so as to be moved out of the path of the finger *t*, is disconnected from the finger and the rod *r* drawn upward, thus depressing the valve *b* 105 until a sufficient quantity of carbid passes by the valve to increase the production of gas and again raise the bell *u*, so as to carry the finger *t* above the lug *s*, when the latter may be again set so as to be engaged by the 110 finger and be operated automatically as before. Should more gas be produced than is required for consumption, the bell *u* will rise sufficiently to receive the surplus gas until 115 the valve acts upon its lower seat and cuts off the supply of carbid. It will be seen that by reason of the peculiar relative contours of the valve *b* and the interior of the case *a* the valve is enabled to operate freely when the case has a charge of carbid therein, the 120 valve practically engaging its seats near its part 1 of greatest diameter. Referring to Fig. 1, it will be seen that when the valve *b* is in the position shown the opening below the valve will be greater in area than the 125 opening above it, insuring free movement of the carbid. The movement of the valve and its stem *c* agitates the grains of carbid and augments the movement thereof. In Fig. 3 the valve *b* is on its lower seat, and assuming that the case *a* above the valve is full of loose carbid it will be seen that if the valve be 130 slowly pushed up it will permit the carbid to pass down, while the valve will gradually

close the orifice at the seat *e* and cut off the flow there, as in Fig. 2, and the carbid in the case will pass down therefrom, while none can interfere with the valve being closed 5 tightly against its upper seat *e*. It will be understood that there is an aperture in the extension of the cover *l* to receive the rod *r*, and this, with other openings, (not shown,) 10 may serve as vents if excessive pressure of gas should by any accidental means be produced in the receiver *k*.

Having thus described my invention, what I claim, and desire to secure by Letters Patent, is—

- 15 1. A carbid-feeding mechanism including a valve-case having fixed opposing inner sides the upper and lower portions of which slope at different degrees of angularity toward the ends of the case terminating at inlet and outlet openings having fixed areas, unyielding valve-seats at the openings, and a valve confined between the said upper and lower portions and limited in its travel by the unyielding valve-seats.
- 25 2. A carbid-feeding mechanism comprising a valve-case the lower portion of which is in the form of a funnel having unyielding relatively long straight sloping sides approaching the perpendicular in degree of angularity and the upper portion of which is in the form of an inverted funnel having unyielding relatively short sloping sides approaching the horizontal in degree of angularity, a valve comprising conical ends having straight faces 35 differing in degree of angularity, the angularity of the lower portion of the valve corresponding substantially to the angularity of the lower portion of the case and the angularity of the upper portion of the valve differing 40 from the angularity of the upper portion of the case, the valve being confined operationally in the case, and seats for the valve.

3. In a carbid-gas generator, the combination with a water-tank, of a valve-case having two opposing valve-seats and an enlarged 45 clear space between the two seats, a hopper communicating with the top of the valve-case, a guide in the hopper, a guide below the valve-case, a valve adapted to move partially through the orifices at the valve-seats and 50 having a guide-stem engaging the said guides, said valve having an enlarged portion intermediate of the ends thereof at either side of which it is adapted to engage one of said seats, a push-bar for the valve, a weight for 55 depressing the valve, and means for operating the push-bar.

4. In a carbid-gas generator, the combination of the water-tank, the gate-valve, the receiver secured immovably to the water-tank, 60 the valve-case attached to the receiver and having the upper valve-seat and the opposing lower valve-seat, the valve having the oppositely-disposed conical ends adapted to engage said seats and having the guide-stems 65 attached to the ends thereof, the guides engaging said stems, the weighted operating-stem connected to said guide-stem, the guide attached to said tank and having the push-bar mounted therein, the lever engaging said 70 push-bar, the coupling-rod connected to said lever, the gasometer-tank, the gasometer-bell operatively engaging said coupling-rod, the gas-pipe extending from the receiver into the bell, and the hopper at the top of the valve-case communicating therewith, substantially 75 as set forth.

In testimony whereof I affix my signature in presence of two witnesses.

JOHN C. KEMP.
